UNITED STATES PATENT OFFICE.

SOLOMON H. GOLDBERG AND WALTER H. HERMSDORF, OF CHICAGO, ILLINOIS; SAID HERMSDORF ASSIGNOR TO SAID GOLDBERG.

MACHINE FOR MAKING CARTONS.

Application filed October 15, 1923, Serial No. 668,484. Renewed March 10, 1927.

This invention relates to a machine for making cartons, and refers more particularly to a machine designed to cut and score a boxboard stock into the finished form of a carton ready for folding, all as part of a continuous operation.

Among the objects of the invention are to provide a machine of the character described, in which the cutting and scoring is done by circular dies instead of with the flat die formerly used; to provide a machine of the character described in which there are positioned gripping rolls of small diameter for gripping the stamped sheet, and driven at a much higher speed than the stamping rolls; to provide a conveyor belt of such width that it permits the waste from the stamped sheet to fall into suitable receptacles, and the stamped sheet itself to pass into a separate collector; to provide in a machine of the character described, means for waterproofing the interior of the box with various substances, as for example, paraffine; to provide a machine of the character described in which the stamping means consists of a lower die roll containing knives and punches, and an upper roll containing recesses of predetermined depth, which regulate the scoring and cutting of the blank; to provide a machine of the character described in which the feeding, stamping, gripping, separating and collecting are done automatically as a continuous operation; to provide a machine of the character described in which all the parts are driven in timed relation; to provide a machine of the character described in which the waste from the carton blank will be separated and collected automatically; to provide a machine of the character described which has few working parts and adapted to produce a maximum of stamped forms as part of a continuous mechanical operation.

In the drawings:

Fig. 1 is a diagrammatic side elevational view of our improved stamping machine.

Fig. 2 is a side elevational view taken from a point opposite to that at which Fig. 1 was taken, with parts in section.

Fig. 3 is a top plan view of the machine.

Fig. 4 is a front elevational view with parts in section, taken on lines 4-4 of Fig. 1.

Fig. 5 is a detail side view of the stamp-

ing and gripping rolls with certain parts in section.

Fig. 6 is a cross sectional view of the paper guiding means. Figs. 7 and 8 are diagrammatic top plan views of the stamping and gripping rolls showing the arrangement of the conveyor and the manner of separating the blanks from the waste.

Referring in detail to the drawings, 1 designates the frame equipped with vertical supporting rods 2, horizontally projecting rod 3 supported by the bar 4. These parts are constructed of steel or other heavy metal. A roll of heavy gauge paper 5, is mounted on the shaft 6, which shaft in turn is mounted on the rollers 7, in the arm 3. This paper has been previously prepared in rolls and is of the usual weight suitable for boxboard manufacture. The paper is fed from the roll 5 through the guide rolls 8, which latter rolls also tend to remove the so called curl of the paper without weakening the fibres, or placing unequal strain thereon.

The underside of the paper is then coated with a waterproofing material such as hot paraffine, by passing over the paraffine bed roll 9, and under the press roll 10. The roll 9 is mounted on the shaft 11 which is driven by the bevel gear 12, the operation of which will be later described. The upper roll 10 is driven in timed relation with the lower roll 9 by means of the gear 13 meshing with the gear 14. The paraffine or other waterproofing material is contained in the tank 15, the contents of which may be heated by the burner 16. It is understood that any manner of heating the coating may be used, such as steam, etc.

The arrangement is such that the lower roll 9 revolves in the hot paraffine, applying it to the underside of the stock being fed thereto. The stock is then fed through the idler rolls 17 connected to the frame as shown.

We may provide longitudinally extending plates 18 bolted as shown at 19 to the frame 100 and disposed on both sides of the sheet being fed forward. Each plate has inwardly projecting lips 20 for guiding the paper through the machine. The paper is then fed between the stamping rolls 20 and 21 mounted on shafts 20^a and 21^a. The lower die roll 20 (Fig. 4) is provided with a series of knives 22 and punches 23 of predetermined con-

figuration, which project from the surface thereof. The punches 23 are spring actuated for ejecting the punched slots from the blank. In the roll shown, there are four 5 identical sets of knives on its periphery, so that one complete revolution of the roll will stamp four forms from the blank. The knives on the die roll 20, whether used for cutting or scoring, are the same height above 10 the face of the roll.

Referring now to the upper roll 21, it is recessed as shown at 23^a, to register with certain of the knives in the lower roll. The 15 operation is as follows: At the instant the knives on the lower roll meet the paper to be cut where there is no recess in the upper roll, the knife will cut through the paper stock. Where there is a recess in the upper roll, the knife on the lower roll will not cut, 20 but will press the paper into the depression in the upper roll, thereby scoring it.

As one of the features of our invention, the stamped sheet is then gripped by the gripping rolls 24 and 25, which latter are 25 revolving at a much higher rate of speed than the stamping rolls, say, 3 to 1. It will be readily seen that the gripping rolls, revolving at high speed will grip the stamped sheet and tend to jerk it away from the 30 stamping rolls. This jerking will have the effect of breaking the sheet where it has been cut, and causing a complete separation between the carton form and incidental waste. This feature is shown in detail in Figs. 7 35 and 8.

After the separation by means of the rollers 24 and 25, the carton form is conveyed to suitable collecting means, by means of the endless conveyor belt 26 revolving on the 40 idler shafts 27 and 28. A carton form 29, which has just been formed, is shown (Fig. 7) as passing between the gripping rolls, while another form, made just previous to it is shown on the conveyor 26, being carried to 45 the collector.

Referring to Fig. 8, the belt conveyor is only wide enough to support the main portion of the box being formed, allowing the waste 30 which has just been separated from 50 the carton form 29, to fall into any suitable collecting means. It will be readily seen that this arrangement allows the formed blank and waste to be separated automatically, the blanks being collected separately from 55 the waste.

Returning now to the drive, we provide a motor 31, having pulley 32 and belt 32^a driving the pulley wheel 33. This pulley wheel has shaft 34 rotating with it, and 60 carrying with it small gear 35 which drives gear 36 located on shaft 36, which in turn rotates gear 36^a, which meshes with large gear 42. The shaft 36^a in turn drives the bevel gear 37 meshing with the bevel gear 38. 65 This bevel gear 38 is mounted on the shaft

40, which shaft terminates in another bevel gear 41, which latter meshes with the bevel gear 12 on the shaft 11, driving the waterproof coating roll 9 and press roll 10 through the gears 13 and 14. The gear 42 meshes 70 with the gear 43 mounted directly above it on the shaft 21^a for driving the upper recessed platen roll 21. The gear 43 in turn meshes with a smaller gear 44 mounted on the stub shaft 45, which shaft also carries 75 gear 46. The gear 46 in turn meshes with small gear 47 mounted on the shaft 48. This shaft carries another gear 49 for driving the upper gripping roll. The gear 49 meshes with the gear 50, which latter gear drives the 80 lower roll 25 which latter roll in turn drives the endless conveyor belt 26.

Returning now to the conveyor belt 26, the lower gripping roll 25 is recessed transversely as shown at 51 to accommodate the belt 26 from which it secures its drive. The depth and length of the recess is such that the upper surface of the belt when placed in the recess, will be flush with the surface of the roll, and the edges of the belt substantially touching the inner sides of the recess. (Fig. 4.) The gripping rolls 24 and 25 may be constructed of metal, rubber, etc., and may have their surface suitably roughened to instantly grip the stamped 95 paper as explained.

The shaft 27 driving the lower gripping roll 25 rotates in the side blocks 52, while shaft 53 driving upper gripping roll 24 rotates in the side blocks 54. It will be 100 noted that the blocks 54 are stationary, and attached to the frame of the machine. The side blocks 52, on the other hand, are held under constant spring tension by means of the screws 55 and coil springs 56. The 105 screw threaded portion of the screw 55 is threaded into the upper block 54. The arrangement is such that the block 52 will give through the action of the spring 56, thus compensating for any difference in the 110 thickness of the paper stock.

Any variations in the thickness of the paper passing through the stamping rolls 20 and 21 is taken up by means of the vertical rod 57 connecting the split bearings 58 115 and 59 in which the shafts 20^a and 21^a bear. The ends of the blocks 60 holding these bearings are adapted to ride in the dovetail portion 61 of the frame.

We provide a scraper 62 mounted on the 120 brackets 63 attached to the frame, which scraper extends transversely of the roll 21 for removing any lint or punched particles of paper which may adhere to this roll.

From the foregoing, it will be seen that 125 we have provided a novel machine for producing carton forms, the cartons adapted to contain many varieties of materials, such as perishable goods of all kinds. The operation is entirely automatic from the roll of 130

stock to the finished form, and adapted to operate continuously for extended periods of time.

We claim as our invention:

- 5 1. In a machine for cutting and scoring blanks, the combination with means for feeding forward a continuous sheet from a roll of paper stock, of continuously rotating opposed cutting and scoring rolls acting on said sheet, gripping rolls adapted to separate the formed blank, an endless conveyor narrower than the lower gripping roll and mounted thereon to remove the blank after eliminating the waste.
- 10 2. In a machine for cutting and scoring blanks, the combination with means for feeding forward a continuous sheet from a roll of paper stock adapted to be continuously fed forward, of continuously rotating opposed cutting and scoring rolls acting on said sheet, gripping rolls adapted to separate the formed blank from the waste, an endless conveyor mounted on the lower gripping roll to remove the blank after eliminating the waste, the whole adapted to operate in timed relation as a continuous operation.
- 15 3. An apparatus for cutting and scoring a continuous sheet to produce blank forms therefrom, the combination with guide plates attached to the frame having lip portions extending over the sheet, cutting, scoring and gripping rolls operating on the advancing sheet, an endless conveyor mounted in a groove on the lower gripping roll for removing the formed blank, after eliminating the waste.
- 20 4. An apparatus for cutting and scoring a continuous sheet to produce blank forms therefrom, the combination with opposed cutting and scoring rolls acting thereon, gripping rolls smaller than the cutting and
- 25 scoring rolls for separating and eliminating the waste from the formed blank, an endless conveyor mounted in a recess in the lower gripping rolls adapted to remove the formed blanks.
- 30 5. An apparatus for cutting and scoring a continuous sheet to produce blank forms therefrom, the combination with opposed cutting and scoring rolls acting thereon, gripping rolls smaller than the cutting and scoring rolls for separating and eliminating the waste from the formed blank, the lower roll being recessed to receive an endless conveyor, and spring tensioned blocks attached to the lower grip roll to automatically compensate for differences in paper thickness.
- 35 6. In an apparatus for cutting and scoring blanks, the combination with means for feeding a continuously advancing sheet, opposed cutting and scoring rolls acting thereon, gripping rolls smaller than the cutting and scoring rolls for separating and eliminating the waste from the formed blank, the lower roll being recessed to receive an endless conveyor, and spring tensioned means cooperating with the lower grip roll to automatically compensate for differences in paper thickness.
- 40 7. In an apparatus of the character described, the combination with means for feeding a continuous sheet, of opposed cutting and scoring rolls acting on said sheet, gripping rolls of less diameter than the cutting and scoring rolls for separating and eliminating the waste from the formed blank, the lower gripping roll being recessed to receive an endless conveyor, and means cooperating with said lower gripping roll automatically compensating for differences in sheet thickness.

SOLOMON H. GOLDBERG.
